(57) **CLAIM**

We claim the ornamental design for a medical syringe, as shown and described.

DESCRIPTION

Fig. 1.1 is a perspective view of a medical syringe showing the new design;
Fig. 1.2 is a top view thereof;
Fig. 1.3 is a bottom view thereof;
Fig. 1.4 is a front view thereof;
Fig. 1.5 is a rear view thereof;
Fig. 1.6 is a left side view thereof; and
Fig. 1.7 is a right side view thereof.

(Continued)

The broken lines shown in the drawing views are included for the purpose of showing environmental structure that forms no part of the claimed design.

1 Claim, 7 Drawing Sheets
